UNITED STATES PATENT OFFICE

JULIAN PAUL TEDFORD, OF OKLAHOMA CITY, OKLAHOMA, ASSIGNOR TO LEON N. FARR, O. R. RANDLE, W. H. COURTNER, AND GEO. W. RIDDLE

ANTIGLARE DEVICE FOR AUTOMOBILES

Application filed December 12, 1931. Serial No. 580,685.

My invention relates to anti-glare devices for use in connection with an electric bulb for an automobile headlight, or the like.

I am aware of the fact that it has heretofore been proposed to mount a reflecting shield upon or in advance of the electric bulb of an automobile headlight. The difficulty experienced in connection with such devices is that the average user will not accurately or properly apply the reflecting shield upon the bulb so that it will be positioned at the required angle, with the result that the reflecting shield may lose a part or all of its efficiency in reducing blinding lights.

In accordance with my invention, I provide a reflecting shield which is mounted upon the forward end or end portion of the bulb, and this shield is carried by an attaching device which, in turn, is secured to a portion of the bulb, preferably the shank of the same. The attaching device, when applied to the shank, is held thereto at a fixed angular position and will, in turn, hold the reflecting shield upon the end or end portion of the bulb in a proper fixed angular position, for rendering efficient service. The invention is of simple construction, may be manufactured cheaply, and may be placed in position so that the reflecting shield will assume the correct angular position, by an inexperienced user.

In the accompanying drawing, forming a part of this specification, and in which like numerals are employed to designate like parts throughout the same,

Figure 1 is a vertical section through the reflecting shield and attaching device, parts in elevation, showing the same in use,

Figure 2 is a side elevation of the shield and attaching device, removed from the bulb,

Figure 3 is a perspective view of the attaching device with the reflecting shield removed, and

Figure 4 is an end elevation of the same.

In the drawing, wherein for the purpose of illustration is shown a preferred embodiment of my invention, the numeral 5 designates a bulb of an electric light, having the usual shank 6, and filament 7. This

shank 6 is held in the usual socket and projects forwardly beyond this socket, as is customary. The bulb 5 is arranged within a parabolic reflector 8, having a lens 9, associated therewith, as is customary.

The numeral 10 designates a reflecting shield. This shield is preferably substantially opaque, and is preferably formed of glass. The outer surface of this shield is preferably covered by a coating 11, which is preferably of some dark color, such as black or gray, and the coating may be of any suitable material, such as paint, shellac, or the like. The inner surface of the reflecting shield constitutes a highly polished reflecting surface, and this reflecting surface is provided by burning or firing a platinum alloy into the concaved surface of the glass shield. While this is preferred, the invention is not necessarily restricted to this precise type of reflecting surface, as the convex side of the shield may be suitably treated to provide a reflecting surface, as is the case of a mirror.

It is thus seen that the concave side of the shield surface has an efficient reflecting surface. The reflecting shield 10 is spherically curved and is adapted to be mounted upon the forward end or end portion of the bulb 5, with its edge 12 or plane arranged at an inclination. I have found that highly satisfactory results are obtainable by having the edge 12 inclined at an angle of about 30° from the vertical, although this precise angle may be varied within limits. This angular disposition of the shield allows the filament to be uncovered throughout substantially the upper half of the bulb, while the shield covers the filament throughout substantially the lower half of the bulb. The edge 12 having all portions thereof in a common transverse inclined plane, permits of the uncovering of the filament toward the upper side of the bulb in a gradual and uniform manner, effecting a superior distribution, or the like.

The attaching device which I provide not only serves to securely hold the reflecting shield upon the forward end or end portion of the bulb, but insures that the shield will

assume the correct angular position, requiring no adjustment after the attaching device has been mounted upon a part of the bulb, such as a shank.

6 This attaching device is preferably formed of spring steel, and includes a lower main strip or body portion 13, including a forward curved arm portion 14, and this forward curved arm portion carries a pair of diverging curved arms 15. The arms 15 are bent inwardly or over at their free ends, affording catches or fingers 16. The curved arm portion 14 constitutes a third arm, which is circumferentially equi-distantly spaced with 10 respect to the arms 15, these three arms snugly receiving and holding the spherically curved reflecting shield 10, the fingers 16 engaging over the edge 12, while fingers 17, formed at the rear end of the arm portion 14, also engage over the edge 12. The reflecting shield 10 is, therefore, securely held in place upon the holding device and assumes the proper angle with relation thereto. The rear end of the strip or body portion 13, ex- 15 tends rearwardly beyond the arm portion 14 and is provided with an attaching socket 18, which is U-shaped, and is adapted to be sprung upon a portion of the bulb, preferably upon the shank 6. The arm portion 14 is longer than the arms 15, and this enables the arms and arm portion to hold the reflector at the selected angular position, when 20 applied to the bulb.

In view of the foregoing description, it 25 will be seen that the reflector may be quickly and conveniently applied to the bulb in the car, without the necessity of removing the bulb from its socket. The socket 18 is mounted upwardly upon the shank 13, and 30 when thus applied, it will automatically cause the reflecting shield to assume the proper angular position upon the bulb.

When applied to the forward end or end portion of the bulb, the rays of light from 45 the filament are reflected upwardly and rearwardly upon the upper portion of the parabolic reflector, and are then projected forwardly by the reflector and inclined downwardly, to strike the road at a suitable 50 distance in advance of the automobile. The device will eliminate the shadows and blinding lights, and will also perceptibly increase the amount of proper illumination upon the road.

55 It is to be understood that the form of my invention herewith shown and described, is to be taken as the preferred example of the same, and that various changes in the size, shape and arrangement of parts may be re- 60 sorted to without departing from the spirit of my invention or the scope of the subjoined claim.

Having fully described my invention, what I claim is:

65 A spherically curved reflecting shield to be

mounted upon the forward end portion of an electric bulb and a separate holding device therefor, said holding device comprising a longitudinal body portion including an arm portion provided at its forward free end 70 with a pair of diverging arms, the arm portion and the arms being longitudinally curved to correspond to the curvature of the shield and having their rear end portions substantially circumferentially equi-distantly spaced, said arms being provided at their free ends with inwardly facing extensions to engage over the edge of the shield and the arm portion being provided adjacent to its rear end with an inwardly projecting extension to engage over the edge of the shield, said arm portion being longer than said arms so that the shield is held at a selected angle, said body portion extending rearwardly beyond the arm portion for a substantial distance, and a U-shaped socket carried by the rear end of the body portion for engaging with the shank of the bulb.

In testimony whereof, I affix my signature.
